2,006,940

BUNG AND A METHOD OF MAKING BUNGS

Henry H. Brockmeyer, Cincinnati, Ohio

Application August 18, 1934, Serial No. 740,425

4 Claims. (Cl. 217—110)

The invention relates to means particularly adapted to prevent seepage of liquids through bungs.

Heretofore, considerable difficulty and inconvenience has been experienced by users of bungs for various purposes, such as sealing bung holes in beer kegs, vinegar barrels, and the like, in preventing seepage of liquids within the containers outwardly through the bung. This is particularly true because bungs are constructed from wood whose grain extends transversely of the bung and in many instances, especially for the reason that presently bungs usually are constructed from wood derived from relatively small trees, the grain does not extend parallel with the inner and outer surfaces of the bung but curves inwardly or outwardly whereby the liquid, particularly beer, which is under relatively heavy pressure within the container, is adapted to seep through the pores in the wood of the bung, or through the channels adjacent the grain. Moreover, the pressure of air or gases within the container is reduced as by escape of such air or gases through the pores or channels, in the bung, adjacent the grain, simultaneously when the liquid within the container seeps therethrough. Since it is advantageous to retain the air or gas pressure within the container, as well as prevent seepage of the liquid from within said container outwardly through the bung, any leakage of air or seepage of liquid is undesirable.

Therefore, an important object of the invention is to provide simple, efficient, practical and economical means to prevent passage of air or gases through a bung and to prevent seepage of liquid through said bung.

Other objects of the invention are to provide dependable means adapted to render the inner surface of a bung impervious to liquids, such as beer, whiskey, and the like; and to provide means which is unlikely to interfere or retard natural expansion of said bung, when contacted by said liquid, for the purpose of sealing the bung hole in which said bung is positioned.

Other objects of the invention are apparent by reference to the hereinafter description.

The invention consists in providing a shield or coating attached to the inner surface of said bung.

The invention, also, consists in the combination of the elements, arrangement of the parts and in the details of the construction, as hereinafter fully explained.

In the drawing:

Fig. 1 is a bottom view of the invention;

Fig. 2 is a section taken on a line corresponding to 2—2 in Fig. 1;

Fig. 3 is a plan view showing a modified form of the invention;

Fig. 4 is a section taken on a line corresponding to 4—4 in Fig. 3;

Fig. 5 is a bottom view, showing a modified form of the invention;

Fig. 6 is a section taken on a line corresponding to 6—6 in Fig. 5;

Fig. 7 is a plan view showing still another modified form of the invention; and

Fig. 8 is a section taken on a line corresponding to 8—8 in Fig. 7.

In the preferred construction of the invention, as shown in Figs. 1 and 2, I provide the usual cylindrical bung 1 having the inwardly inclined side edges 2. The bung is formed from any suitable material, such as wood, and has its inner side 3 compressed. On the inner side 3 is fixed the 20 coating 4 formed from shellac.

When the bung 1 is inserted in the usual bung hole in the conventional keg or container (not shown) the liquid within the container is adapted to contact the side edges 2, of the bung 1, and cause the bung to expand or swell in sealing contact with the walls of the bung hole. The liquid, and gas or air pressure, within the container, is adapted to contact the coating 4 on the inner surface 3 of the bung and prevent seepage or escape 30 of said liquid or gas or air pressure from within the container and outwardly through pores or channels adjacent the grain of the wood from which the bung 1 is formed.

In Figs. 3 and 4 are shown a modification of the 35 invention which comprises the bung 5 having the usual cylindrical-shape orifice 6 in its outer side 7 which may be utilized for the purpose of receiving a suitable tool for inserting into or removing the bung from the usual bung hole in the conventional keg or container (not shown). The inner side 8 of the bung has compressed therein the recess 9 whose side walls 10 are inclined outwardly and inwardly. Received in the recess 9 is the plate 11, formed from suitable material, such as stain-

less steel. The recess 9 may be pressed, by suitable machinery, in the inner side or end 8 of the bung 5, whereby the pores and grain of the wood which run transversely of the axis of the bung, 50 from which the bung 5 is formed, are compressed. When the bung 5 is inserted in the usual bung hole in the usual keg or container (not shown) the liquid and air or gas pressure, within the container contacts the outer surface of the plate 11 55

and is prevented from passing through the pores or channels of the bung 5.

In Figs. 5 and 6 is shown still another modification of the invention which comprises the bung 5 12 having formed in its outer surface 13 the orifice 14 for receiving a suitable removal tool. The inner side 15, of the bung 12, is compressed. Fixed to the inner side 15, of the bung 12, is the cup 16, which may be formed from any suitable metal, such as stainless steel. The rim 17, of the cut 16, is embedded in the bung.

When the bung 12 is inserted in the usual bung hole in the usual keg or container (not shown) the liquid and air or gas pressure, within the container 15 contacts the outer surface of the cup 16 and is prevented from passing through the pores, channels, or other passages, in the bung 12.

In Figs. 7 and 8 is shown still another modified form of the invention which comprises the bung 20 18 having pressed in its inner side 19 the corrugations 20. When the corrugations 20 are pressed into the inner surface of a bung, by any suitable mechanism, the inner surface of the bung is compressed whereby any pores, channels, or other 25 passages, which may extend from the inner surface 19 to the outer surface 21, of the bung 18, are closed. The coating 22, formed from shellac, is fixed to the corrugations 20.

When the bung 18 is inserted in the usual bung 30 hole in the usual keg or container (not shown) the liquid and air or gas pressure, within the container contacts the outer surface of the coating 22 and is prevented from passing through the pores, channels, or other passages, which may 35 extend from the inner surface 19 to the outer surface 21 of the bung 18.

An advantage of the invention is that the liquid 40 within the container, in which the bung is positioned, is permitted to contact the tapered side edges of the bung for the purpose of permitting the bung to swell or expand in sealing contact with the walls of the bung hole in which the bung is positioned, and yet the liquid, or gas or air 45 pressure, within the container is prevented from seeping or escaping through the pores, channels, or other passages, which may extend from the inner to the outer sides of the bung.

Still another advantage of the invention is 50 that the inner side of the bung may be quickly and economically prepared for the purpose of preventing said seepage or escape of said liquid,

gas or air pressure from within the container outwardly through the bung.

It is, therefore, quite apparent that I have invented a highly desirable and practical device for the purposes intended and which may be utilized with dependability for the purpose of sealing the inner side of a bung to prevent passage of liquid, gases or air through the bung. 5

While I believe that the form of the invention illustrated in the drawing and referred to 10 in the above description, as the preferred embodiment, is efficient and practicable, yet realizing that the conditions concurrent with the adoption of the device will necessarily vary, I desire to emphasize the fact that changes in 15 the details may be resorted to, when required, without sacrificing any of the advantages of the invention as defined in the claims.

Various changes may be made in the general 20 form and arrangement of mechanical parts described without departing from the invention. Hence I do not limit myself to the precise details of the materials or the size and shape thereof as set forth, but consider myself at liberty 25 to make such changes and alterations as fairly fall within the spirit and scope of the appended and final claims.

What I claim as new and desire to secure by Letters Patent is:

1. A wooden bung having the grain running 30 transverse of its axis, the inner end of said bung being coated with shellac, and said shellac being bonded to and compressed within and around the fibres of said inner end.

2. A wooden bung having the grain running 35 transverse of its axis, the inner end of said bung being coated with water resistant material, and said water resistant material being bonded to and compressed within and around the fibres of 40 said inner end.

3. A wooden bung, as defined in claim 2 having the fibres at the inner end of the bung in corrugated compressed condition.

4. The method of producing a wooden bung 45 consisting of forming a plug of wood with its grain transverse of its axis and its inner end being coated with wet shellac, and then while said shellac is still soft compressing the inner end of the plug sufficiently to cause the shellac to permeate within and around the fibres of 50 said inner end.

HENRY H. BROCKMEYER.
